US00D900529S

(12) **United States Design Patent** (10) Patent No.: **US D900,529 S**
(45) Date of Patent: **** Nov. 3, 2020**

(54) **ELECTRIC PRESSURE COOKER**

(71) Applicant: **LG ELECTRONICS INC.**, Seoul (KR)

(72) Inventors: **Hyunhee You**, Seoul (KR); **Sungkyung Kim**, Seoul (KR); **Joo-Gyeom Kim**, Seoul (KR); **Kyoungmin Baek**, Seoul (KR); **Woonkyu Seo**, Seoul (KR); **Hyunsun Yoo**, Seoul (KR); **Yousook Eun**, Seoul (KR); **Hyejin Choi**, Seoul (KR)

(73) Assignee: **LG ELECTRONICS INC.**, Seoul (KR)

(**) Term: **15 Years**

(21) Appl. No.: **29/678,132**

(22) Filed: **Jan. 25, 2019**

(51) LOC (12) Cl. **07-02**
